UNITED STATES PATENT OFFICE.

EMIL S. HALTER, OF PATERSON, NEW JERSEY.

DYEING MACHINE.

1,417,825.

Specification of Letters Patent. Patented May 30, 1922.

Application filed February 5, 1921. Serial No. 442,665.

To all whom it may concern:

Be it known that I, EMIL S. HALTER, a citizen of the United States, residing at Paterson, in the county of Passaic and State 5 of New Jersey, have invented certain new and useful Improvements in Dyeing Machines, of which the following is a specification.

In treating skeins with liquids, as in 10 dyeing, a well known hand operation is to shift sticks on which the skeins are hung and which rest on the sides of the vat through the liquor first one way along the vat, one after another, and then the other 15 way, and after this has been done sufficiently to insure good permeation the skeins are changed so as to immerse the part of each which was last exposed. The object of this invention is to provide a machine in the 20 operation of which the known benefits and advantages of this hand treatment will be as far as possible retained and at the same time the great loss of time avoided which is incident in the hand operation to 25 the shifting of the skeins being effected one after another instead of all at once.

In the accompanying drawings,

Figure 1 is a side elevation of the improved machine;

30 Figure 2 is an end elevation, partly in section;

Figure 3 is a fragmentary side elevation on a larger scale; and Figure 4 is a sectional view of a detail.

35 The vat is indicated at *a*.

On a base *b* is arranged a hydraulic lifting ram *c* the head of whose movable member *c'* carries a horizontally elongated support *d* formed by spaced and rigidly connected channeled rails *d'*. A horizontal series of parallel rotary shafts *e* are journaled in bearings *f'* on the top of the support *d*, shafts *e* being arranged transversely of said support and also of the vat *a*, parallel with 40 one long side of which the support *d* is arranged.

45 Carriers *f* are pivoted on the shafts *e*, hanging pendent therefrom. Pivoted on each shaft is also a toothed segment *g*, which is pinned to the carrier, as at *h*.

The lower end of each carrier has suitably secured thereto a horizontal spindle *i*, and on this spindle is a skein support in the form of a reel *j* which in the present case is journaled on the spindle. The skeins *A* are adapted to be looped over the reels *j* as

shown in Figure 1 so as to hang pendent therefrom, partly immersed in the liquor in the vat *a*.

Each carrier is adapted to be oscillated 60 on the shaft *e* as an axis, and in the present case, there being a plurality of the carriers, I provide for moving them back and forth in synchrony, each always in the same direction as any other carrier. To this end, *k* 65 is a rack arranged to slide on suitable projections *l* extending from the support *d*, the teeth on the rack engaging the teeth of the segments *g* and one end of the rack preferably moving in a suitable guide *m*. When 70 the rack is reciprocated the carriers oscillate each past the perpendicular position (Figure 1) to right and left thereof about as far as shown in Figure 3, so that the skeins *A* are swept through the liquor in order to 75 effect permeation thereof by the liquor. Of course if the carriers are all oscillated in synchrony, that is, in constant parallelism where they are pivoted, as in the present case, a greater number can be accommodated 80 in the same space than would otherwise be possible.

For changing the position of the skeins so that the part of each which is at times exposed will at other times be immersed in the 85 liquor means is provided for rotating the reels *j* on their spindles *i*. Gearing *n*, here in the form of a sprocket-and-chain connection, connects each shaft *e* with the corresponding reel *j*, so that the shaft is the driving 90 member for the reel and rotation of the shaft causes rotation of the reel. The several shafts are equipped with gears *o* which intermesh with each other, so that rotation of any one causes rotation of all the others 95 and consequently of the respective reels. The several shafts *e* may be rotated from a suitably driven drive shaft *p* which drives a counter shaft *q* through a worm and worm-wheel connection *r*, the counter shaft driving 100 one of the shafts *e* through intermeshing gears *s* and *t* on shafts *q* and *e*.

The rack *k* may be reciprocated from the intergeared system of shafts *e* in any way, as by being provided with a transversely slotted head *u* in which plays a wrist pin *v* on a crank arm *w* secured to a counter shaft *x* which is suitably journaled parallel with one of the shafts *e* and is adapted to be rotated therefrom by the intermeshing gears *y* and *z* 110 on these shafts *x* and *e* (see Figure 4). The speed of rotation of the reels may be varied

with reference to their oscillating speed by changing the gears $y z$ for others of different sizes.

By mounting each reel on a carrier oscillatory laterally of the pendent skeins, the reel being revoluble on the carrier on a horizontal axis, I obtain by mechanical means a practically exact simulation of the hand operation. That is, the skeins move back and forth through the liquor in a manner which not only insures good permeation of the skeins and constant agitation or mixing of the liquor but little withdrawal of the skeins therefrom at the end of each stroke, which is important where the liquor is (as in dyeing) hot, in that it avoids dissipation of the heat of the liquor; and all movements of the skeins take place with the least frictional action thereon, in which respect my present machine represents a still further advance in the art than is afforded by the machine patented to me (under my then name of Emil Schnurrenberger) by U. S. Letters Patent No. 1,350,740. In respect to the rotation of the reels I do not wish it to be understood that my invention is limited to the rotation being continuous or always in the same direction, as in the example herein given.

Having thus fully described my invention, what I claim as new and desire to secure by Letters Patent is:—

1. A machine for treating skeins in a liquor bath, including, with a vat, a carrier over the vat oscillatory laterally of the pendent skeins, and between limits of movement approximately equidistant from the surface of the bath, and a reel revoluble on the carrier on an approximately horizontal axis and over which the skeins are looped and from which they hang pendent.

2. A machine for treating skeins in a liquor bath, including, with a vat, a carrier over the vat oscillatory on a pivot laterally of the pendent skeins, and between limits of movement approximately equidistant from the surface of the bath, and a reel revoluble on the carrier on an approximately horizontal axis and over which the skeins are looped and from which they hang pendent.

3. In combination, with a vat, a pendent carrier pivoted over the vat and oscillatory laterally of the pendent skeins and between limits of movement approximately equidistant from the surface of the bath, and a reel revoluble on the lower part of said carrier on an approximately horizontal axis and over which the skeins are looped and from which they hang pendent.

4. In combination, with a vat, and supporting means a rotary driving member journaled on an approximately horizontal axis, in the supporting means a carrier over the vat oscillatory laterally of the pendent skeins, a reel revoluble on the carrier on an axis approximately parallel with the first axis, and over which the skeins are looped and from which they hang pendent, and means to transmit rotary rotation from said member to the reel.

5. In combination, with a vat, a rotary driving member journaled on an approximately horizontal axis, a carrier pivoted concentrically with said member over the vat and oscillatory laterally of the pendent skeins, a reel revoluble on said carrier on an axis approximately parallel with the first-named axis and over which the skeins are looped and from which they hang pendent, and means to transmit rotary motion from said member to the reel.

6. In combination, with a vat, a carrier over the vat oscillatory laterally of the pendent skeins, a reel revoluble on the carrier on an approximately horizontal axis and over which the skeins are looped and from which they hang pendent, and separate means, respectively engaged with the carrier and reel, to oscillate the former and rotate the latter.

7. In combination, with a vat, a plurality of rotary intergeared driving members journaled on approximately horizontal and parallel axes, a carrier pivoted concentrically with each of said members and over the vat and oscillatory laterally of the pendent skeins, a reel revoluble on each of said carriers on an axis approximately parallel with the first-named axes and over which the skeins are respectively looped and from which they hang pendent, and means to transmit rotation from each member to the corresponding reel.

8. In combination, with a vat and supporting means, pendent carriers pivoted in the supporting means on approximately parallel and horizontal axes and over the vat, skein supports on the lower parts of the respective carriers arranged approximately parallel with said axes and over which the skeins are looped and from which they hang pendent, and means to oscillate said carriers in synchrony each always in the same direction as the other and between limits of movement approximately equidistant from the surface of the bath.

In testimony whereof I affix my signature.

EMIL S. HALTER.
